ROOM COOLER

Joseph Askin, Buffalo, N. Y., assignor to Fedders
Manufacturing Company, Inc., Buffalo, N. Y.

Application October 31, 1934, Serial No. 750,831

10 Claims. (Cl. 62—103)

This invention relates to heat exchange apparatus of the type generally known as unit coolers or forced draft coolers, and it has particular reference to a cooling unit including a cooling coil and a fan for circulating air through the cooling coil, with which is associated means for regulating or controlling the humidity of the circulated air.

Unit coolers find application in auditoriums, large storage rooms, or "walk-in" boxes, in which refrigeration is desired, but which do not admit of an elaborate installation of more or less permanent machinery. According to the plan of the cooler which forms the subject matter of this invention, it is proposed to devise a compact unitary apparatus, which may be mounted as desired in the room to be cooled, and to include in such apparatus a refrigerating coil, and a fan, and also to provide means on the coil to regulate the humidity of the circulated air.

To this end, the invention, in one aspect, takes the form of a casing or cabinet which is roughly divided into a cooling compartment and a fan or motor compartment,—the arrangement being such that room air is drawn into the fan compartment and is forced through the coil compartment and thence back into the room. In passing through the coil, the air is diverted in a suitable fashion so as to create the path of circulation best suited for the intended purposes.

Moreover, the cooling coil is provided with fins which serve to increase the cooling effect, and which are also formed with a multiplicity of pockets, so disposed as to retain varying amounts of condensed moisture. This condensate is held up to a certain value, in the pockets formed on the fins, where it is accessible for re-evaporation and return to the air when conditions require. With this invention, appreciable excesses of moisture are removed from the treated air, but complete dehydration is not effected, and hence a suitable and more or less automatic control of the humidity is obtained.

The invention further contemplates various other improvements in unit coolers, the nature of which need not be elaborated upon here, since they are pointed out in the following description and claims. A typical embodiment of the invention is illustrated in the accompanying drawings, in which:

Fig. 1 is a perspective view of a unit cooler embodying the present invention;

Fig. 2 is a rear elevation, with the fan and motor removed, and certain parts broken away to illustrate details of construction;

Fig. 3 is a section on the line 3—3 of Fig. 2;

Fig. 4 is a fragmentary section on an enlarged scale, through the cooling element, showing particularly the pocket formation of the fins and tubes; and,

Fig. 5 is an enlarged fragmentary front elevation of the fins and tubes.

As shown in Fig. 1, the apparatus comprises a cabinet or casing 10, having continuous side, top, and bottom walls and a front wall 11 which is substantially open, to reveal a cooling coil, generally designated by the numeral 12. The front wall 11 is advantageously disposed at an angle, and the cooling coil, as will be made clear hereinafter, is also set at an angle which may be equal to, or more or less than, the slope of the front wall. By this construction, cooled air, which is discharged through the front wall, is diverted upwardly, thus chilling any warm air in the room, and creating a circulatory path entering the cooler through its rear wall. By directing the cold air towards the ceiling, a maximum circulatory effect for the velocity of the draft may be effected.

The cabinet 10 may be mounted in the room by any suitable means, such, for example, as the brackets 13 which suspend the unit from the ceiling. Other mounting arrangements may be provided, as the immediate situation may warrant.

Referring now to Fig. 3, it will be observed that the cabinet 10 is divided into two major compartments 14 and 15 by a vertical wall or partition 16. These two compartments will be termed the fan or motor compartment, and the cooling compartment, respectively. It will also be observed that the rear portion of the cabinet 10 and the major portion of the front wall 11 are open, and, by referring to Fig. 2, it will be seen that the central part of the dividing wall 16 is also open, thereby providing a horizontal passage for the circulation of air from the room, through the fan compartment, into the cooling compartment, and thence back into the room.

The fan compartment 14 is provided on opposite side walls with brackets 17, from which depends an electric motor 18, driven by any suitable source of current, not shown. To the shaft of the motor 18 is secured a fan 19, which projects forward into the aperture of the vertical wall 16. As shown in Figs. 2 and 3, the wall 16 may be formed from a sheet of metal to provide an annular rim or shroud 21 for the blades of the fan, so that the circulated air is properly directed through the cabinet 10. The ends of

the wall 16 are bent over or flanged, to form edges adapted to receive bolts 22 and 23, by means of which the wall is secured to the cabinet.

The cooling unit 12, which is mounted in the cooling compartment 15, comprises a pair of opposed and spaced frames 25 and 26, between which extend a plurality of interconnected sections of horizontally disposed tubing 27, the ends of which are connected by return bends 28 disposed outside of the frames 25 and 26. The frames are soldered or otherwise are suitably secured to the tubes, thus making a substantially unitary cooling assembly. The tube extremities 29 and 31 pass through suitable apertures in the wall 16, and provide for the introduction and withdrawal of a refrigerant or cooling medium through the unit. The apparatus herein described is assumed to be employed with a volatile liquid refrigerant which is delivered from a compressor-condenser system (not shown), to an expansion valve 32, thence into the connecting pipe 29 and through the cooling unit,—the connecting pipe 31 providing for the return of expanded refrigerant to the compressor. As is usual in such systems, the expansion valve operation may be controlled thermostatically, by means of an expansion bulb 33, connected to the return line 31, and serving to control the valve 32.

In connection with this brief description of the refrigerant system preferred in connection with the present invention, attention is invited to the trough or apron 34, which is disposed under the expansion valve 32 and the return line 31 in the fan compartment. This trough is welded or otherwise secured to the wall 16, and projects therethrough, to spill any liquid entrapped therein into the lower part of the cooling compartment. The provision of such apron is advantageous, since one of the purposes of the present invention is to provide a controlled and limited dehydration of the room air, in the event it becomes too moist. Under certain operating conditions, excess moisture condenses on the refrigerant return line, and would, unless removed, drip back into the room and possibly on commodities stored therebeneath.

Reverting now to the construction of the cooling unit 12, it will be observed in Figs. 4 and 5 that the horizontal tubes 27 are provided with fins 36 which are disposed longitudinally of the tubes. The fins 36 are of generally undulatory contour, being formed with alternate crests and troughs 37 and 38, and the trough portions are formed with cylindrical saddle portions 39 which partially embrace the tubes 27. By referring to Fig. 4, it will now be noticed that when the tube bank is disposed at an angle to the vertical, the forward edges, side walls, and saddle portions of the fins define small pockets 41, which serve to retain a part of the moisture which may condense from time to time on the cooling unit, as the temperature of wet warm air is reduced. In the absence of such pockets, all condensate would run off the fins and tubes, to the lower part of the cooling compartment 15, whereas, by providing such pockets, only the excess of the condensate is so removed,—the balance which is caught in the large number of pockets being retained in small quantities, and in the air path, where it may be re-evaporated when conditions require.

In order to mount the cooling unit 12 at a desired angle to the vertical, the upper and lower edges of the end frames 25 and 26 are bent over to provide inwardly projecting flanges 43 and 44 respectively. The upper flange 43 is formed with

a slot 45, through which passes a bolt 46, projecting to the exterior of the cabinet 10, to receive a wing nut 47. The lower flange 44 is provided at its rear edge with a rolled portion 48 forming a bearing for a hinge pintle 49 which is connected to a plate 51, secured to the lower wall of the cabinet. It will be understood that the cooling unit 12 may thus be swung back and forth on the pintles 49, to the extent provided by the length of the slot 45, and may be held at any desired angle to the vertical by tightening the wing nuts 47.

This adjustable mounting of the cooling unit provides for adequate flexibility in varying the amount of moisture which may be retained in the pockets 41 of the radiating fins 36. Thus, it will be observed that the amount of moisture to be retained may be estimated for some mean or average condition, and such condition approximately cared for by suitable design and dimensioning of the fins themselves. Desired variations from this mean may be effected by changing the inclination of the unit, since, if the unit is vertical, with the type of fins herein described, the capacity of the pockets is practically nothing. With such a setting, the cooling unit would act to remove substantially all the excess moisture from the room. As the unit is tilted back, however, the capacity of the fins to retain moisture is increased, and hence the unit does not dehydrate the air below a desired value. It will also be noticed that the variation of the inclination of the cooling unit also serves to vary the direction of the air path.

It has not been found necessary to provide special forms of pipe connections for the refrigerant lines 29 and 31, when the hinge connection is disposed at the bottom of the cabinet. The actual movement of the cooling unit at this point is very slight, and the inherent flexibility of the tubes is sufficient to compensate for such linear movement as may take place.

A catch basin 53 is disposed at the bottom of the compartment 15, to receive any excess condensate, and also moisture dripping from the open end of the trough 34. This basin is connected to a drain by means of a connecting pipe 54, passing through the bottom wall of the cabinet 10. As cold water, collecting in the basin 53, might cause some "sweating" and dripping from the exterior of the cabinet, during periods of dehydration, the basin is insulated by a pad 55, interposed between the cabinet wall and the basin and partition wall 16, so that undue heat transfer between these parts cannot be effected.

In operation, it will be assumed that the cabinet is suitably mounted in a room to be cooled, and the cooling unit is connected to a refrigerant compressor, while the motor is driven to rotate the fan 18 and thus circulate the room air through the cooling compartment. As the relatively warm air strikes the refrigerant tubes with their attached fins, its temperature is reduced, and excess moisture, for that temperature, condenses on the fins. A part of this moisture drains to the bottom of the cooling compartment, and is removed through the pipe 54. The balance of the condensate is retained in the pockets 41. This circulation and cooling of the warm air continues, until a condition would be reached where the air had been cooled to the desired temperature, and partially dehydrated, but not fully dehydrated. If the room air should now be changed, as by opening the room and introducing more warm air, or by placing a wet article in the room, fur-

ther limited dehydration and cooling would occur, to restore the desired conditions. If, on the other hand, the temperature of the room should be increased, as frequently happens in service, the circulated air would take up the necessary amount of moisture from the condensate held on the large surface of the fins, rather than extract moisture from some commodity in the room. The extent to which this moisture is available is dependent, of course, on the actual size and proportions of the unit, and also the inclination at which the cooling element 12 is set.

It will be understood that while the invention has been described with reference to a single embodiment, it is not intended that it should be so limited, but it is desired to encompass all other embodiments or modifications which fall within the scope of the following claims.

I claim:

1. A heat exchange device comprising a cabinet having a passage therethrough and being adapted to be mounted with said passage arranged horizontally, a partition within the cabinet dividing the passage therein into a fan compartment and a cooling compartment, said cooling compartment of the cabinet being formed with an end face extending upwardly at an angle to the vertical, a tank mounted at the bottom of the cabinet in the cooling compartment thereof, a cooling unit comprising a pair of spaced frame members arranged parallel to said end face and secured at their top ends to the cabinet and resting in said tank at their lower ends, a plurality of tube coils mounted between said frames and each having fin members mounted thereon at right angles to the frames, a motor driven fan in the fan compartment and means secured to the cabinet for mounting said fan coaxially with said cabinet passage, said partition having an enlarged opening for receiving and directing the air stream from the fan to the cooling unit.

2. A heat exchange device comprising a cabinet having a passage therethrough and being adapted to be mounted with the passage arranged horizontally, a partition disposed transversely in the cabinet and dividing the passage therein into a fan compartment and a cooling compartment, said cabinet at the bottom of the cooling compartment therein cooperating to form a tank, a cooling unit mounted transversely in the cooling compartment and resting in said tank, and a motor driven fan in said fan compartment, said partition having an enlarged opening for receiving and directing the air stream from the fan to the cooling unit.

3. A heat exchange device comprising a cabinet having a passage therethrough and being adapted to be mounted with the passage arranged horizontally, a partition disposed transversely in the cabinet and dividing the passage therein into a fan compartment and a cooling compartment, said cabinet at the bottom of the cooling compartment therein cooperating to form a tank, a cooling unit mounted transversely in the cooling compartment and disposed to permit drainage of condensate therefrom into said tank, a control valve disposed in said fan compartment and communicating with said cooling unit, an apron in the fan compartment secured to the partition and extending therethrough, said apron being disposed beneath said valve to receive condensate therefrom for direction to the tank, and a motor driven fan in said fan compartment, said partition having an enlarged opening for receiv-

ing and directing the air stream from the fan to the cooling unit.

4. A heat exchange device comprising a cabinet adapted to be mounted in a room to be cooled, said cabinet having a front wall inclined to the vertical and a horizontal passage extending through said cabinet and wall, a partition in said cabinet dividing the same into a fan compartment and a cooling compartment, a fan mounted in said fan compartment, a cooling coil mounted in said cooling compartment, said cooling coil being provided with frame members to hold said coils in unitary relationship, said coil being hingedly connected to one wall of said cabinet and being releasably secured to an opposite wall of the cabinet, whereby the inclination of said coil to the vertical is adjustable and the circulation of air in said room may be varied.

5. A heat exchange device comprising a cabinet adapted to be mounted in a room, said cabinet having a front wall inclined to the vertical and a horizontal passage extending through said cabinet and wall, a partition in said cabinet dividing the same into a fan compartment and a cooling compartment, a cooling coil mounted in said cooling compartment, said coil being provided with a frame for holding the coil in unitary relationship, the ends of said coil being disposed adjacent an end of said frame, said coil ends terminating in conduits extending from said cabinet, a hinge connection for said coil and frame disposed between the cabinet and frame adjacent said coil ends, and a releasable connection for said frame disposed at a remote point in said cabinet, whereby said cabinet is mounted for adjustable tilting movement and said coil ends have substantially no movement throughout the range of adjustment.

6. In combination with a cabinet divided into a fan compartment and a cooling compartment and having a horizontal passage therethrough, a fan mounted in said fan compartment to effect the circulation of air through the cabinet, a cooling coil mounted in the cooling compartment to cool the air so circulated, said cooling coil comprising a plurality of interconnected lengths of tubing, fins disposed on said lengths to effect the rapid interchange of heat between the air and said fins and tubes and to receive moisture condensed from the air as its temperature is so reduced, said fins being formed with drainage portions and pocket portions, said drainage portions being inclined to direct moisture condensing thereon to the bottom of said cabinet, said pocket portions retaining moisture condensing thereon, and a catch basin disposed at the bottom of said cooling compartment to receive draining condensate.

7. A room cooler comprising a cabinet having an open front and back, a partition in said cabinet dividing the same into a fan compartment and a cooling compartment, a fan mounted in the fan compartment to circulate air through the cabinet, a cooling unit mounted in the cooling compartment, said cooling unit comprising a plurality of tubes having heat radiating fins mounted thereon, said fins being formed to provide spaced pockets between the fins and tubes, whereby limited quantities of condensed moisture are retained in a plurality of units along said tubes and in the path of air circulated through said cabinet, and a catch basin disposed in the cabinet below said cooling unit to receive excess moisture condensing on said cooling unit and draining therefrom.

8. A heat exchange apparatus for cooling and conditioning air in a room comprising a cabinet formed with passages therethrough and being adapted to be mounted in a room with said passages arranged horizontally, said cabinet being divided into a fan compartment and a cooling and conditioning compartment, a fan in said fan compartment for circulating air in said room through said cabinet and said cooling and conditioning compartment, a cooling unit mounted in said cooling compartment, said cooling compartment comprising a plurality of connected horizontally disposed tubes constituting a conduit for the circulation of a cooling medium through said cooling compartment, fins secured to said tubes, said fins being formed with pocket portions for the reception of moisture condensed from air circulated through said cooling compartment, whereby said moisture will be at times entrapped in said pockets for retention adjacent said tubes and will be at other times re-evaporated and returned to the air circulating through said compartment.
9. Apparatus for modifying the temperature and humidity condition of room air, comprising a substantially rectilinear frame divided into a fan compartment and a conditioning compartment, a fan mounted in said fan compartment for circulating air through said apparatus and through said conditioning compartment, said conditioning compartment containing a heat exchange member formed with a plurality of horizontally disposed fluid conducting tubes, said tubes being provided with radiating fins, said fins being of undulated contour and disposed longitudinally of the tubes, said fins further being formed with saddle portions engaging over portions of said tubes, whereby certain portions of

said undulated fins lie below said saddle portions, said tubes and fins being inclined at an angle to the horizontal in said frame to provide a plurality of moisture receiving pockets, whereby portions of excess moisture condensing on said fins and in said pockets will be retained therein for evaporation when the conditioned air reaches a condition of moisture deficiency. 5

10. A heat exchange device for cooling and conditioning the air in a room comprising a cabinet having a passage therethrough and being adapted to be mounted with the passage arranged horizontally, said cabinet being divided into a fan compartment and a cooling compartment, a fan in said fan compartment for circulating room air through said cabinet and said cooling compartment, a cooling unit mounted in said cooling compartment, said cooling unit comprising a plurality of horizontally disposed tubes connected at their ends to provide a conduit 20 for a cooling medium, frame members disposed at the ends of said tubes to support the same, said frame members being positioned in said cabinet at an inclination to the vertical, cooling fins mounted longitudinally of the tubes and 25 secured in spaced relation to the top and bottom sides thereof, said fins being of undulated form and having saddle portions engaging over limited areas of said tubes and other portions projecting forwardly thereof, said other portions 30 being disposed at an angle to the horizontal and forming, with said tubes and saddle portions, a plurality of moisture retaining pockets on the uppermost of said fins, and means disposed below said tubes to entrap moisture overflowing 35 said pockets and condensing in said lower fins.

JOSEPH ASKIN.
